UNITED STATES PATENT OFFICE.

JESSE ALEXANDER, OF BROOKLYN, NEW YORK.

DESIGN FOR A TYPE-WRITER FRAME.

No. 38,327.

Specification for Design.

Patented Nov. 27, 1906.

Application filed December 5, 1905. Serial No. 290,487. Term of patent 14 years.

To all whom it may concern:

Be it known that I, JESSE ALEXANDER, a citizen of the United States, residing at 130 Milford street, Brooklyn, county of Kings, and State of New York, have invented a new, original, and ornamental Design for a Type-Writing-Machine Frame, of which the following is a full, clear, and exact description.

In the drawings, Figure 1 is a perspective view of a type-writing-machine frame em-

bodying the design of my invention, taken from the front. Fig. 2 is a perspective view of the same, taken from the rear.

I claim—

The ornamental design for a type-writer frame, as shown.

JESSE ALEXANDER.
